United States Patent Office

Des. 212,488
Patented Oct. 22, 1968

212,488

FLOOR POLISHER HEAD

Donald Lee, 3633 Strandhill Road,
Shaker Heights, Ohio 44122

Filed Jan. 29, 1968, Ser. No. 10,340

Term of patent 14 years

(Cl. D37—3)

FIG. 1 is a top plan view showing the design of my invention;

FIG. 2 is a side elevational view showing my new design;

FIG. 3 is a front elevational view showing my new design.

The broken line representations of parts of the floor polisher head in FIGS. 1, 2 and 3 are for illustrative purposes only.

I claim:

The ornamental design for a floor polisher head, as shown and described.
